UNITED STATES PATENT OFFICE

CARLOS STRICKHouser, OF PHILADELPHIA, PENNSYLVANIA, ASSIGNOR TO
FRIEDBERGER-AARON MANUFACTURING COMPANY, OF PHILADELPHIA,
PENNSYLVANIA, A CORPORATION OF PENNSYLVANIA.

DESIGN FOR LACE EDGING.

47,764.

Specification for Design.

Patented Aug. 24, 1915.

Application filed June 9, 1915. Serial No. 33,187. Term of patent 7 years.

To all whom it may concern:

Be it known that I, CARLOS STRICKHouser, a citizen of the United States, residing in Philadelphia, county of Philadelphia, and State of Pennsylvania, have invented a new, original, and ornamental Design for Lace Edging, of which the following is a specification, reference being had to the accompanying drawings, which form a part thereof.

The drawing is a plan view of a portion of lace edging showing my design.

The same comprises a tip or border of peculiar configuration the marginal loops of

which constitute prolongations of the cross-bars spanning the ribbon space and connecting the tip or border with the opposite sewing-on edge.

I claim:

The ornamental design for lace edging, as shown and described.

In testimony of which invention, I have hereunto set my hand, at Philadelphia, on this 8th day of June, A. D. 1915.

CARLOS STRICKHouser.
